Inventor,

Royal G. Reid

By *McH. Loughridge* Attorney

UNITED STATES PATENT OFFICE.

ROYAL G. REID, OF BROOKLYN, NEW YORK.

TOY CHIME.

1,335,855.

Specification of Letters Patent.

Patented Apr. 6, 1920.

Application filed October 13, 1919. Serial No. 330,254.

To all whom it may concern:

Be it known that I, ROYAL G. REID, a citizen of the United States, and resident of Brooklyn, in the county of Kings and State 5 of New York, have invented certain new and useful Toy Chimes, of which the following is a specification.

This invention relates to toy chimes and may be used for amusement or advertising 10 purposes. Its objects are to provide a simple means for obtaining a continuous variety of sounds or chime that is comparatively inexpensive and easily operated. These objects are obtained by the construction illustrated in the accompanying drawings in 15 which, Figure 1, is a side view of the device with one of the covers removed showing the interior mechanism and Fig. 2 is a view at right angles to Fig. 1, with the covers shown 20 in section.

This device, as shown, consists of a plurality of bell domes having different tones and a means for intermittently ringing either dome. The bell dome 11 is supported by the 25 shaft 14 and to which the handle 13 is secured. This shaft is shouldered and has an extension 15 which supports the bell dome 12 by the upset end 16. On the extension 15 a sleeve 17 is provided having an arm 18 30 formed integral with the off-set 19 and the arm 20 which terminates in the weight 22. It will readily be understood from Fig. 2 that a rotating motion applied to handle 13 will cause the weight 22 to rotate about the 35 shaft 15 as a center, the arm 20 moving freely in the opening 21 between the bell domes as shown.

The escapement wheel 31 is securely keyed at 32 to shaft 15 and is therefore rigid with 40 the handle 13. The escapement pawl 33 is pivoted at 34 to the arm 18 and thus rotates with the arm 20 about the center 15 of the escapement wheel. The rotation of arm 20 therefore gives a vibratory motion to pawl 45 33. On one end of this pawl the hammer 35 is secured by the off-set connection 38 and on the other end the hammer 36 is secured by the off-set connection 37. This brings hammer 36 into the bell dome 12 and hammer 35 into the bell dome 11 and from the vibratory motion of the pawl each hammer alternately strikes its respective bell dome. 50

It is an element of my invention to make the bell domes of different tone so that the 55 operation of the device will alternately give different notes. The preferable way of do-

ing this is to make the bell dome 11 thicker than bell dome 12, as indicated in Fig. 2. However, any of the well known methods of varying the tone may be used such as varying 60 their shape, etc.

This device may be provided with more than two bells, for instance, a smaller bell dome may be placed within dome 11 on shaft 14. I have indicated a construction 65 of this kind using, however a coil spring gong 41 instead of a bell. This is shown in an incomplete form in Fig. 1 where the back stroke of hammer 35 strikes the gong at a. The gong is secured to shaft 14 by 70 the collar 42.

This illustrates and describes the principles of my invention which it is obvious may be applied in a variety of ways. I do not therefore wish to be limited to the construction here shown except as defined by the 75 scope of the appended claims.

Having thus described my invention, I claim:

1. In a sound producing device of the 80 class described, the combination of a plurality of bells, an escapement, an arm arranged to revolve about the axis of said bells and means including said escapement for alternately ringing said bells by the revolution 85 of said arm.

2. In a sound producing device of the 90 class described, the combination of a plurality of bells of different tones, an escapement, an arm arranged to revolve about the axis of said bells and means operated by said escapement for alternately ringing said bells by the revolution of said arm.

3. In a sound producing device of the 95 class described, the combination of a plurality of bells supported by a handle through their axis, an escapement, a weighted arm arranged to revolve about the axis of said handle and means operated by said escapement for alternately ringing said bells by 100 the revolution of said arm.

4. In a sound producing device of the 105 class described, the combination of a plurality of bells supported by a handle, an escapement wheel secured to said handle, a weighted arm arranged to revolve about the axis of said handle, an escapement pawl secured to said arm and means for alternately ringing said bells by the revolution of said arm with relation to said handle. 110

5. In a sound producing device of the class described, the combination of a plural-

ity of bells supported by a handle, an escapement wheel secured to said handle, a weighted arm arranged to revolve about the axis of said handle, an escapement pawl secured to said arm having off-set extensions at each end supporting a hammer and means for alternately ringing said bells by the revolution of said arm.

6. In a sound producing device of the 10 class described, the combination of a plurality of bells placed in spaced relation with their concave sides adjacent, a handle sup-

porting said bells, an escapement wheel secured to the axis of said handle, a weighted arm arranged to revolve about the axis of 15 said handle and through the space between said bells, an escapement pawl secured to said arm and means for alternately ringing said bells by the revolution of said arm with relation to said handle.

Signed at Ridgewood, in the county of Queens and State of New York this 3rd day of October, A. D. 1919.

ROYAL G. REID.
